INKING APPARATUS FOR TYPEWRITING MACHINES HAVING TYPE CYLINDERS

Oskar Fischer, Kappeihof, near Friedrichshafen, Germany

Application January 23, 1932, Serial No. 588,399,
and in Germany May 1, 1926

12 Claims. (Cl. 197—150)

My invention relates to improvements in inking apparatus such as used for example in typewriting machines and more particularly in typewriting machines comprising type cylinders. More particularly my invention relates to improvements in inking apparatus of the type comprising a casing containing the ink, an inking member such as a roller adapted to be passed across the delivery opening of the said casing and the type, for transmitting the ink from the said opening to the type.

One of the objects of the improvements is to provide an apparatus of this class in which a regulated amount of ink is transmitted from said delivery opening to the type, so that the letters are printed in a uniform shade. With this object in view my invention consists in providing a valve for closing the said delivery opening and means for unseating the said valve for supplying a uniform amount of ink.

Another object of the improvements is to provide an apparatus in which the amount of ink supplied by the valve can be regulated for printing in darker or lighter shades, and with this object in view my invention consists in providing means in connection with the valve for unseating the same more or less according to the desired shade of printing.

Further, an object of the improvements is to provide an apparatus in which the ink taken by the roller is uniformly distributed before applying the same to the type, and with this object in view I provide the ink-container with a spreading surface adjacent to the opening thereof and in position for having the roller move across the same after taking the ink from the opening and before applying the same to the type.

Other objects of the improvements will appear from the following description.

For the purpose of explaining the invention several examples embodying the same have been shown in the accompanying drawing, in which the same letters of reference have been used in all the views to indicate corresponding parts. In said drawing,

Fig. 1 is an elevation showing the inking apparatus mounted on the top plate of a typewriting machine,

Fig. 1a is a detail sectional plan view taken on the line 1a—1a of Fig. 1,

Fig. 2 is an elevation viewed from the left in Fig. 1,

Fig. 3 is a top plan view of Fig. 1,

Fig. 4 is an elevation viewed from the rear in Fig. 1,

Fig. 5 is a sectional elevation on an enlarged scale showing the casing containing the ink and the valve controlling the delivery of ink from said casing,

Fig. 6 is a similar sectional elevation showing a modification, and

Fig. 7 is a detail view showing a modification.

In the example shown in Figs. 1 to 5 the inking apparatus comprises a casing 1 for the ink connected or made integral with a tubular member 21 which is rectangular in cross-section. The said tubular member is adapted to be placed on a pillar 22 rising from the top plate 49 of the typewriting machine, and it is adapted to be fixed in position by means of a screw 23 having a milled head and screwing in a threaded hole of the pillar 22. The tubular member 21 is made integral with a plate 24 projecting laterally therefrom and carrying an eye 17. Within the casing 1 there is a tubular member 2 which extends transversely through the same from one wall to the other, and which is open at one end and closed at the opposite end by a bottom 5 which bottom is provided with a central hole 5'. The said hole is normally closed by a valve cone 4 fixed to or made integral with a plug 4' screwing in the tubular member 2. The left hand part of the tubular member 2 communicates with the casing 1 through bores 3. To the screw plug 4' an arm 6 is secured which carries a pin 7, and the said pin is engaged by the bifurcated end of the upwardly directed arm of a bell crank lever 8 pivotally mounted on the pillar 22 at 8'. The laterally projecting arm of the said bell crank lever is formed with a slot 9 engaged by a link 10 connected with an arm 13 through the intermediary of a universal joint comprising a block 10' connected respectively with the link 10 and the arm 13 by pivot bolts 11 and 12 disposed at right angles. The arm 13 is connected with the printing mechanism of the typewriting machine and it is adapted to be moved upwardly and downwardly whenever the printing mechanism is operated for printing a letter. By such upward and downward movement of the link reciprocating rocking movement is imparted to the screw plug 4' for opening and closing the hole 5' and permitting a slight amount of ink to be delivered from the casing 1.

On the eye 17 a lever 16 is rockingly mounted to the top end of which a U-shaped leaf spring 15 is secured which carries an inking roller 14 adapted, as the lever swings, to advance in yielding engagement over one of the types of the type cylinder 19, over a surface 20 formed on the outer

wall of the casing 1 and on the tubular member 21, and over the hole 5' opening through the said surface. To an arm 16' of the lever 16 a pin 25 is secured which is engaged by a claw formed at 6 the top end of an arm 18, which arm is connected with the printing mechanism and adapted to be moved upwardly and downwardly upon each printing stroke of the type cylinder 19. The arm 18 is made in two sections 18 and 18' jointed to 10 each other at 18² and adapted to be rocked to bring the claw into and out of engagement with the pin 25, as is shown in Fig. 1 in full and broken lines, a spring 18³ normally holding the upper part of the arm 18 in engagement with the pin 25.

15 The link 10 is adapted to be shifted relatively to the slot 9 for varying the range of the opening movement of the valve cone 4, and for this purpose it is connected by a link 40 with a block 41 slidably mounted in a slot 42 of a plate 42 secured to the top plate 49. On a pivot bolt 46 rising from the plate 42 a bell crank lever 45 is mounted one arm of which is formed with an enlarged end formed with a cam slot 44 engaged by a pin 43 made integral with the block 41. The 20 other arm of the said bell crank lever carries a pin 47 which extends upwardly therefrom and through a slot 48 made in the plate 49. By rocking the bell crank lever 45 by means of the pin 47, the block 41 is shifted in a direction for rocking the link 10 relatively to the slot 9, so that the range of the rocking movement imparted to the bell crank lever 8, in response to the vertical movement of arm 13, is increased or reduced, and the range of shift in axial direction of the screw 25 plug 4' is correspondingly increased or reduced.

30 It will be perceived that the apparatus includes an ink fountain comprised of the container 1, with an orifice in its wall, and an ink-spreading surface 20, to which the ink may pass 35 as it emerges from the orifice.

40 The levers 8 and 16 together (in the form shown in Figs. 1-5) and the lever 16 alone (in the form shown in Fig. 6) constitute in the two cases reciprocating mechanism, performing essentially 45 the same organized steps in the operation.

The operation of the inking apparatus is as follows:

45 By the printing operation the type cylinder 19 is thrown forwardly in Fig. 1, and the arm 13 is moved upwardly and downwardly for rocking the screw plug 4' and opening and closing the hole 5' thus allowing a slight amount of ink to be delivered through the said hole. Simultaneously the arm 18 is moved upwardly and downwardly, and by the upward movement the roller 14 is first moved across the type of the type cylinder 19 which has been set into printing position, and thereafter the roller is moved across the surface 20 and the hole 5', thus taking a slight 50 amount of ink from the said hole and spreading the same on the surface 20. At the beginning of the movement of the type cylinder 19 towards the platen, the roller 14 is for a slight distance carried along, by reason of the elasticity of the leaf 55 spring 15, until by the swinging of lever 16 the roller passes from engagement with the type cylinder, permitting the same to continue its movement towards the platen. If it is desired to change the shade of the print made by the 60 type cylinder the link 10 is shifted relatively to the slot 9.

65 If the supply of ink within the casing 1 is exhausted, the said casing is removed from the pillar 22 and sent to the salesman for being refilled in 70 the factory, another casing being in the mean-

time placed on the machine. It will be noted that, together with the casing 1, the roller 14 and the lever 16 carrying the same are removed and sent to the salesman. I have found that for giving satisfactory results it is desirable that the 80 operator be not able to fill the casing 1 with ink, because it is important that always a high quality ink be used. Further, it is desirable that at the same time the roller 14 be sent to the manufacturer, because the said roller, which ordinarily 85 consists of rubber, wears out after a certain length of time, and it should be replaced by a new roller whenever a new supply of ink is needed.

90 In the construction so far described the mechanism for opening the valve 4, 5' is independent of the lever 16 and the inking roller 14. But I wish it to be understood that my invention is not limited to this feature, and that in some cases I provide an inking apparatus in which the valve is opened by the lever 16. This modification is 95 shown in Fig. 6, in which the said lever 16 opens the valve through the intermediary of the inking roller 14. As shown in the said figure, a ring 31 is fixed in a hole made in the wall of the casing 1, and the said ring is formed with a conical hole 100 engaged by a valve cone 26, the rounded end 32 of the said valve cone extending outwardly through the hole of the ring 31. The stem 27 is embedded in a socket 28 of a screw plug 29 screwing in the wall of the casing 1 opposite to the 105 ring 31. Between the said wall and a collar 27' of the stem 27 there is a spring 30 which tends to force the valve cone 26 outwardly and into position for closing the hole made in the ring 31. By screwing the plug 29 more or less inwardly or 110 outwardly the range through which the valve cone 26 may (by the spring-borne roller 14) be shifted is varied, and thus the amount of ink delivered from the casing 1 may be varied. Between the head 36 and a nut 33 an arm 34 is clamped 115 to the plug 29, and the said arm carries a pin 35 adapted to engage in any one of a series of sockets 37, made in the wall of the casing 1, for securing the screw plug 29 in adjusted position.

120 In the position of the apparatus shown in Fig. 6 the roller 14 moves across the wall of the casing 1 and it engages the rounded end 32 of the valve cone 26 and temporarily forces the same inwardly, in opposition to the tension of the spring 30, thus allowing a slight amount of ink to be 125 delivered through the bore of the ring 31.

130 In the modification shown in Fig. 7 the valve cone 4'' is rounded at its rear part, its surface preferably following stream lines. I have found that when thus shaping the cone the ink flows 135 more readily and uniformly through the hole 5'.

135 While in describing the invention reference has been made to particular examples embodying the same, I wish it to be understood that my invention is not limited to the constructions shown in the drawing, nor to the use of the inking apparatus in typewriting machines, and that various changes may be made in the general arrangement of the apparatus and the construction of its parts, without departing from the invention.

140 I claim:

1. An inking apparatus, comprising an ink container, a valve controlling the delivery of ink from said container, a spring acting on said valve for closing the same, means for adjusting the tension 1 of said spring, and a member adapted to be moved across the opening of said valve for taking ink delivered therethrough and adapted to open said valve.

2. In inking apparatus, in combination with 1

type to be inked, a fountain including an ink container and having an orifice through which ink may pass, and a valve in said orifice, reciprocable mechanism adapted with each reciprocation to shift said valve, such mechanism being equipped with a roller which in the range of reciprocation passes successively across such orifice and over the face of the type to be inked.

3. In inking apparatus, in combination with type to be inked, a fountain including an ink container, and having an ink-spreading surface and an orifice through which ink may pass from the container to the spreading surface, and a valve in such orifice, reciprocable mechanism adapted with each reciprocation to shift said valve, such mechanism being equipped with a roller which in the range of reciprocation passes successively over the ink-spreading surface and over the face of the type to be inked.
- 10 4. In inking apparatus, in combination with type to be inked, a fountain including an ink container, and having a orifice through which ink may pass from the container, and a valve in such orifice, reciprocable mechanism, and adjustable connection between such mechanism and the valve, whereby with each reciprocation of the mechanism the valve may be shifted through a range that is variable within the discretion of the operator, the said mechanism being equipped with a roller which in the range of reciprocation passes successively across such orifice and over the face of the type to be inked.

- 25 5. In inking apparatus, in combination with a reciprocable type carrier, a fountain including an ink container, and having an orifice through which ink may pass from the container, and a valve in such orifice, mechanism reciprocable in response to reciprocation of the type carrier and adapted with each reciprocation to shift said valve, the said mechanism being equipped with a roller which in the range of reciprocation passes successively across such orifice and over a type face upon said type carrier.

- 40 6. In inking apparatus, in combination with a reciprocable type carrier, a fountain including an ink container and having an orifice through which ink may pass from the container, and a valve in such orifice, mechanism reciprocable in a plane transverse to that in which the type carrier reciprocates and adapted with each reciprocation to shift said valve, the said mechanism being equipped with a yieldingly mounted roller which in the range of reciprocation passes successively across such orifice and over a type face upon said type carrier.

- 45 7. In inking apparatus, in combination with type to be inked, a fountain including an ink container and having an ink-spreading surface and an orifice through which ink may pass from the container to the spreading surface, and a valve normally closing such orifice and protruding above the level of such ink-spreading surface, and a reciprocable member equipped with a roller, said

roller in the range of member reciprocation passing successively over the ink-spreading surface and the face of the type to be inked and in passing over the ink-spreading surface making unseating engagement with the so protruding valve.

8. An inking apparatus, comprising an ink container, a valve associated with said container and controlling the delivery of ink therefrom, the operating mechanism of a typewriting machine, means controlled by said operating mechanism for opening and closing said valve, and means for adjusting said means for opening and closing said valve for varying the amount of ink delivered to said valve.

9. An inking apparatus, comprising an ink container, a valve controlling the delivery of ink from said container, a screw plug on which the valve cone is mounted, the operating mechanism of a typewriting machine, and mechanism controlled by said operating mechanism for turning said screw plug for opening and closing said valve.

10. An inking apparatus, comprising an ink container, a valve controlling the delivery of ink from said container, a screw plug on which the valve cone is mounted, the operating mechanism of a typewriting machine, mechanism controlled by said operating mechanism for turning said screw plug for opening and closing said valve, and means for adjusting said mechanism for varying the opening movement of said valve.

11. In inking apparatus, in combination with type to be inked, a fountain including an ink container and having an ink-spreading surface and an orifice through which ink may pass from the container to the spreading surface, and a spring-backed valve normally closing such orifice and protruding above the level of such ink-spreading surface, and a reciprocable member equipped with a yieldingly mounted roller, said roller in the range of member reciprocation passing successively over the ink-spreading surface and over the face of the type to be inked and in passing over the ink-spreading surface making unseating engagement with the so protruding valve.

12. In inking apparatus, in combination with type to be inked, a fountain including an ink container and having an ink-spreading surface and an orifice through which ink may pass from the container to the spreading surface, and a spring-backed valve normally closing such orifice and protruding above the level of such ink-spreading surface, adjustable means for limiting the range of valve movement, and a reciprocable member equipped with a yieldingly mounted roller, said roller in the range of member reciprocation passing successively over the ink-spreading surface and over the face of the type to be inked and in passing over the ink-spreading surface making unseating engagement with the so protruding valve.

OSKAR FISCHER.
